UNIT HEATER

Carl W. Sundberg, Detroit, Mich., assignor to Carrier Corporation, Syracuse, N. Y., a corporation of Delaware

Application August 24, 1948, Serial No. 148,269

Term of patent 7 years

(Cl. D81—10)

To all whom it may concern:

Be it known that I, Carl W. Sundberg, a citizen of the United States, residing at Detroit, in the county of Wayne, State of Michigan, have invented a new, original, and ornamental Design for a Unit Heater, of which the following is a specification, reference being had to the accompanying drawing, forming part thereof, in which:

Figure 1 is a front perspective view of the unit heater embodying my new design; and

Figure 2 is a perspective view illustrating the rear of the unit heater.

I claim:

The ornamental design for a unit heater, substantially as shown.

CARL W. SUNDBERG.
